PIPE

Patrick Sullivan, Brookline, Mass.

Application December 27, 1939, Serial No. 311,160

4 Claims. (Cl. 131—203)

This invention relates to improvements in a pipe and more particularly to an improvement which may be incorporated in the manufacture of new pipes or added to old pipes to improve the smoking quality of the pipes by eliminating the moisture in a novel manner.

It is an object of my invention to provide means for eliminating moisture in a pipe which is economical in cost, which does not modify the exterior shape of the pipe, which eliminates the tendency to "bubbling" as the pipe is smoked and which can be readily removed for cleaning.

It is further an object of my invention to eliminate the moisture in a pipe either from the tobacco or from the mouth of the user by causing the moisture to travel out of the smoke passage into a chamber removed therefrom in which the moisture will be dried up by the heat from the bowl.

More specifically it is an object of my invention to provide a vertical bore across the smoke passage which forms a chamber in the side of the bowl, and to mount a capillary absorbent member in the smoke passage and extending into the chamber whereby the moisture will be absorbed thereby and will be dried out in the chamber outside of the smoke passage.

Further objects and advantages of my improvements will be more readily apparent from the following description of a preferred embodiment thereof as disclosed in the attached drawing, in which:

Fig. 1 is a side elevation of the pipe;

Fig. 2 is an exposed view showing a side elevation of the three principal parts of the pipe;

Fig. 3 is a vertical sectional view of the bowl showing the absorbent member in place;

Fig. 4 is a sectional view taken on the plane indicated 4—4 in Fig. 1;

Fig. 5 is a side elevation of the holder and capillary member; and

Fig. 6 is a similar view of a modified form thereof.

The pipe includes the usual bowl 10 and removable stem 12. It will be understood that the pipe may be made in various shapes other than the straight pipe shown.

The chamber 14 of the bowl is formed with annular ridges 16 which tend to prevent packing the tobacco too tightly and tend to prevent the juice from the tobacco from running down the side of the bowl. The bowl part 10 has a short stem 18 provided with a smoke passage 20 and the removable stem 12 is formed with a nipple 22 adapted to fit tightly into the stem 18. 55

A vertical bore 24 is formed in the base of the bowl extending across the smoke passage and forming a chamber 26 in the side of the bowl 10. An internally threaded bushing 28 fits tightly in the opening 24. A screw plug 30 is removably secured in position by threaded engagement with the plug 28.

The plug 30 has an integral tubular extension 32 having slots 34 in the side wall thereof. The 10 tubular portion 32 forms a holder for a capillary absorbent member 36 which may be a piece of pulp wood or other suitable substance such as a short length of cotton wicking or asbestos. The tubular holder fits closely the entrance to the chamber 26 but is open at its upper end, and the absorbent plug 36 may extend beyond the holder as illustrated to permit ready removal therefrom.

The nipple portion 22 of the stem 12 may be 20 formed with ears 38 adapted to fit the slot 40 of screw plug 30 so that the stem may be used as a screw driver to remove the screw plug 30 for cleaning.

Various modified arrangements of the slots or 25 openings in the holder for the absorbent may be used, for example, in Fig. 6 the holder 42 is formed with a spiral slot 44.

It will be noted from Fig. 4 that the holder 30 for the absorbent capillary member 36 extends across the middle of the smoke passage. It is preferable that the area blocked off by the holder 32 constitute from one-third to one-half of the entire cross sectional area of the smoke passage.

In use, drawing of the smoke from the bowl 35 causes the moisture in the smoke to be absorbed by the capillary member 36 and the moisture will travel toward the top of the member 36 and will be dried out in the chamber 26 due to the heat from the bowl of the pipe. It should be 40 particularly noted that there is no pocket or trap formed to collect moisture, and therefore there is no tendency towards "bubbling" or other noisy operation during smoking. The holder 32 is preferably of metal such as aluminum and the heating of the metal also assists in drying the smoke, and in drying out the moisture absorbed by the capillary member. The height of the holder 32 may be varied to suit particular

50 conditions, in fact it may be desirable to employ two sizes of holders, either of which may be used depending upon whether the weather is warm or cold. In cold weather it is desirable that the holder be relatively longer than in warm weather in order to keep the smoke dry.

The device works to some extent as a filter and tends to keep the tobacco in the bowl from entering the stem; should clogging occur adjacent to the holder 32 it is only necessary to blow forward through the stem to release the particles of tobacco which may become lodged adjacent to the tube. It is particularly to be noted that my improvement may be incorporated in pipes as they are manufactured or added to old pipes without any change in the external shape of the pipes.

The heating of the metal member within the smoke passage has a beneficial action in drying and sterilizing the smoke even if the absorbent member is not employed. The metal tube could thus be used without openings in the side wall and if desired to more evenly distribute the heat from the upper chamber down to the base of the tube, a liquid such as water or alcohol or a gas may be sealed in the tube.

I claim:

1. A pipe having a bowl and a smoke passage leading from said bowl, said pipe having an opening in the base of the pipe into the smoke passage and a chamber formed in the side of the bowl above said opening, a holder mounted in said opening extending across said smoke passage and into said chamber, said holder being smaller in diameter than said smoke passage whereby the smoke may flow around said holder through said passage, and an absorbent member carried within said holder, said holder having openings to permit the moisture from the smoke to be absorbed by said absorbent member, which moisture will tend to dry out in said chamber.

2. A pipe having a bowl and a smoke passage leading from said bowl, an opening formed in the base of the pipe into the smoke passage, a threaded bushing fixed in said opening, a tubular metal holder having a threaded head whereby said holder is adapted to be removably secured to said bushing, said holder being smaller in diameter than said smoke passage whereby the smoke may flow around said holder through said passage, said pipe having a chamber formed inside of the bowl above the smoke passage into which said holder extends, a capillary absorbent member removably retained within said holder, the upper end of which extends beyond the top of said holder into said

chamber, said holder having a slot in the side thereof to permit contact between the smoke and said capillary absorbent member whereby the moisture will be absorbed by said member and travel into said chamber and will be dried out by the heat of the bowl.

3. In a tobacco pipe, the combination of a bowl and stem, said bowl having a smooth, straight bore forming a smoke passage leading from the bowl to the stem, said bowl having a chamber formed in the side wall of the bowl and having an entrance opening from said smoke passage, a metallic holder removably secured to the base of said bowl extending across said smoke passage and into said chamber, said holder closely fitting the entrance opening to said chamber, said holder being smaller in diameter than said smoke passage whereby the smoke may flow around said holder, a capillary absorbent member carried by said holder and projecting above the upper end of said holder into said chamber, said holder having an opening in the side wall thereof to permit contact between the smoke and the absorbent member whereby moisture and impurities are absorbed by said member and dried out in said chamber from the heat of the bowl.

4. In a tobacco pipe, the combination of a bowl and stem, said bowl having a smooth, straight bore forming a smoke passage leading from the bowl to the stem, said bowl having a chamber formed in a side wall of the bowl and having an entrance opening into said smoke passage in the top wall thereof, a metallic holder insertable through the base of said bowl and threadedly secured to the base of said bowl, said holder extending across said smoke passage into said chamber and said holder closely fitting the entrance to said chamber, said holder being smaller in diameter than said smoke passage whereby the smoke is free to flow around said holder, a pulpwood absorbent member carried within said holder and, projecting above the upper end of said holder into said chamber, said holder having openings in the side wall thereof to permit contact between the smoke and said pulpwood member whereby moisture absorbed by said pulpwood member will be dried out at the upper end of said absorbent member within said chamber.

PATRICK SULLIVAN.
